ATTACHE CASE

Nathan Weltz, 2049 Ryer Ave., New York, N.Y. 10457

Filed Nov. 24, 1970, Ser. No. 26,148

Term of patent 14 years

Int. Cl. D3—01

U.S. Cl. D87—5

FIG. 1

FIG. 1 is a perspective view of an attache case, showing my new design;

FIG. 2 is another perspective view thereof, showing the attache case in the closed position;

FIG. 3 is a top plan view thereof in the closed position;

FIG. 4 is a side elevational view thereof;

FIG. 5 is an end elevational view thereof; and

FIG. 6 is a bottom plan view thereof.

The characteristic feature of the design resides in a substantially flat, U-shaped, rigid and pivotally connected two-pieced element forming a top frame assembly extending part-way down alongside the outside portion of gusseted end panels and is provided with a closure disposed centrally between a pair of carrying handles secured to the two-piece frame elements; the top frame

opening formed when the attache case is opened extends the full width of the case with the gusseted end panels being opened to their fullest extent; and the side wall panels which are rectangular in shape are provided with square corners.

I claim:

The ornamental design for an attache case, substantially as shown and described.
